United States Patent Office.

EDWARD SMEETH, OF CHICAGO, ILLINOIS.

Letters Patent No. 96,157, dated October 26, 1869.

IMPROVED CONDENSER FOR ALCOHOL-STILLS.

The Schedule referred to in these Letters Patent and making part of the same.

To all whom it may concern:

Be it known that I, EDWARD SMEETH, of Chicago, in the county of Cook, and State of Illinois, have invented an Improvement in Alcohol-Condensers; and I do hereby declare that the following is a full, clear, and exact description thereof, reference being had to the accompanying drawings, making part of this specification, in which—

Figure 1 is a perspective view of a coil of condensing-pipe, having short waste-pipes leading therefrom into the discharge-pipe, and also draw-off cocks applied to short pipes leading into the discharge-pipe.

Figure 2 is a sectional view of the coil, the waste and draw-off pipes, and the discharge-pipe.

Figure 3 is a modification of the condenser of figs. 1 and 2.

Similar letters of reference indicate corresponding parts in the several figures.

This invention relates to an improvement on the condensing-apparatus of spirit-stills; and consists in providing the condenser with means whereby a quantity of watery residuum can be retained at a given height in the lowest bends of the worm, and all rising above such height allowed to escape back into the still, as will be hereinafter explained.

To enable others skilled in the art to understand my invention, I will describe its construction and operation.

In the accompanying drawings—

A represents a condensing-worm, through which the alcoholic and watery vapors are conducted, on their way from the still.

The coils are arranged so as to retain in their lowest bends the watery residuum, through which the vapors are required to pass on their way through the coil.

From each one of the bends of the coil A depends a pipe, b, which forms a communication with a discharge-pipe, B, leading back into the still, above the high-liquid mark therein.

To each pipe b, a cock is applied, as shown in figs. 1 and 2, for drawing off the contents from the bends of the coil A, whenever it is necessary to do so.

Just at the points required for the high-water mark, in the several coils, pipes a are applied, which pipes communicate with the discharge-pipe B, and serve as overflow-pipes, for preventing the fluid from rising above the desired height in the coils.

In the condenser represented in figs. 1 and 2, each one of the lowest bends of pipe A is provided with an overflow-pipe, a, and a draw-off pipe, b.

In fig. 3, I have represented a modification of the above plan, which consists in applying to the discharge-pipe B, at a point between the draw-off pipe b, nearest the still C, and this still, an arched pipe, g, between the limbs of which a cock, c, is applied to the pipe B. This arched pipe g rises a little above the point required for the high-water line in the lowest bends of pipe A, so that the liquid will stand at the same level in the arched pipe g that it does in the bends of pipe A.

When the cock c in pipe B is shut, the liquid resulting from condensation of the vapors passing through pipe A, will accumulate in pipe B, and rise in the bends of the pipe A, to a given height, after which the liquid will overflow in the arch g, and escape back into the still.

This latter arrangement enables me to effect the overflow of the surplus liquid, and also the discharge of all the liquid from the pipe A, by means of a single overflow-pipe and a single cock, applied to the pipe B, while, in the arrangement shown in figs. 1 and 2, an overflow-pipe and a cock are required for each one of the lowest bends of the pipe A.

I am aware, that in the well-known Adams still, the condensing-vessels are provided with short draw-off pipes, which are provided with cocks, and communicate with a pipe leading back into the still, which latter is provided with cocks, for shutting off communication from any one of said vessels. This still is not provided with overflow-pipe, for automatically conducting the liquid from the vessels.

Having described my invention,

What I claim as new, and desire to secure by Letters Patent, is—

One or more overflow-pipes applied to a still, in such manner as to retain part of the liquid resulting from condensation of vapor in the lower portions of such condenser, and allow the surplus liquid to escape back into the still, substantially as described.

EDWARD SMEETH.
